UNITED STATES PATENT OFFICE.

ELOF ANDERSON AND NATHAN W. FLETCHER, OF BATAVIA, ILLINOIS, ASSIGNEES, BY DIRECT AND MESNE ASSIGNMENTS, TO TURBINE MOTOR TOOL COMPANY, OF CHICAGO, ILLINOIS, A CORPORATION OF ILLINOIS.

ROTARY ENGINE.

SPECIFICATION forming part of Letters Patent No. 774,547, dated November 8, 1904.

Application filed April 3, 1903. Serial No. 150,884. (No model.)

To all whom it may concern:

Be it known that we, ELOF ANDERSON and NATHAN W. FLETCHER, citizens of the United States, residing at Batavia, county of Kane, State of Illinois, have invented a certain new and useful Improvement in Rotary Engines; and we declare the following to be a full, clear, and exact description of the invention, such as will enable others skilled in the art to which it pertains to make and use the same, reference being had to the accompanying drawings, which form a part of this specification.

Our invention relates generally to engines, and more particularly to rotary engines of the turbine type.

It is desirable to diminish the flow of motive fluid through an engine when the load is removed therefrom in order to avoid the waste of motive fluid and also to obviate the racing of the engine and the consequent useless wear thereon.

The primary object of our invention is to provide a rotary engine of the turbine type, in which the flow of motive fluid through the engine will be automatically restricted when the engine is relieved of its load and in which the maximum flow of motive fluid will be restored when work is again imposed upon the engine.

A further object of our invention is to provide a turbine the direction of rotation of which may be readily reversed.

A still further object of our invention is to provide a rotary engine of the class referred to which will be simple in construction, inexpensive in manufacture, and efficient in use.

Our invention, generally described, consists in a rotary shaft upon which is mounted a turbine comprising a hub and a series of radial vanes, the hub having ports therethrough on either side of each vane, the ports on the corresponding side of each of the several vanes being adapted to simultaneously register with motive-fluid supply-ports through the shaft to effect rotary motion in one direction, rotary motion in an opposite direction being effected

by simultaneously bringing the ports on the opposite side of each of the several vanes into register with the supply-ports.

Our invention further consists in uniting the turbine to the shaft so as to have a slight rotary motion relative thereto, whereby the extent of registry of the ports through the hub with the supply-ports in the shaft may be varied.

Our invention will be more fully described hereinafter with reference to the accompanying drawings, in which the same is illustrated in a convenient and practical form, and in which—

Figure 1 is an elevational view; Fig. 2, a sectional view on line 2 2, Fig. 1; Fig. 3, a sectional view on line 3 3, Fig. 1; Fig. 4, a view similar to Fig. 3, showing the parts in position to effect rotary motion in a reverse direction; Fig. 5, a sectional view on line 5 5, Fig. 3; and Fig. 6, a sectional view on line 6 6, Fig. 1.

Similar reference characters are used to designate similar parts in the several figures of the drawings.

B designates a shaft, which is rotatably supported by any suitable means—such, for instance, as the posts A' and A'', which are united by a base A. The top of the post A' supports a strap a', which completes the bearing around the shaft at such point. The upper end of the post A'' is provided with a ring a'', the interior surface of which is outwardly tapered. A bushing C is located within the ring a'' and is prevented from rotating relatively thereto by any suitable means—such, for instance, as extending a short tube c' through the ring a'' into engagement with the bushing C.

C' indicates a conduit communicating with the tube c' and leading from a source of motive fluid—such, for instance, as an air-compressor or a reservoir containing compressed air.

The shaft B is provided with a portion B', which tapers from a maximum diameter at the center of the shaft B to a minimum exterior diameter at the end thereof, which ex-

tends within the bushing C. The portion B' of the shaft is provided with an interior chamber B², which is closed at its end by any suitable means—such, for instance, as the plug 5 b². Two or more ports b³ extend through the wall of the portion B' of the shaft, placing the interior B² thereof in communication with an annular groove c, formed in the interior surface of the bushing C and which is in communication with the tube c'. A plurality of ports b', which are shown as three in number, spaced at equal distances apart, lead from the hollow interior B² to the exterior surface of the enlarged portion B' of the shaft.

15 A turbine is mounted upon the portion B' of the shaft and closely engages the exterior surface thereof. The turbine comprises a hub D, from which extend a plurality of radial vanes D', which in the present instance 20 are shown as three in number. Located at either side of the vanes are disks D², which extend radially around the hub D. The vane is retained longitudinally upon the shaft by any suitable means—such, for instance, as 25 lock-nuts G' and G², located around the shaft B and projecting into engagement with the respective ends of the hub D. The opposite surfaces of the several vanes D' are concave and of such a curvature that the vanes gradually increase in thickness from the hub to 30 their upper peripheries. Extending through the hub D on either side of and adjacent to the vanes are ports e' and e², respectively. The several ports e' are so spaced apart that 35 they may simultaneously register with the ports b', leading through the shaft to the hollow interior B² thereof, as shown in Fig. 4. The ports e² are likewise so spaced apart that they may simultaneously register with the 40 ports b' when the vane and shaft are relatively rotated to the position shown in Fig. 3. When one set of the ports e' and e² register with the ports b', the other set are closed by the exterior surface of the shaft between the 45 ports b'.

In order that the turbine and shaft may be relatively rotated a distance necessary to bring into register either of said ports e' or e² with the ports b', a slot d is provided through 50 the hub D, into which projects a pin b, fixed to the portion B' of the shaft. When the ports e² register with the ports b', the pin b engages the end of the slot shown Figs. 1 and 6. When, however, the turbine is in position to effect a registry between the ports e' and b', the pin b engages the other end slot d.

In order that either series of ports e' or e² may only partially register with the ports b' when there is no load upon the engine, or, in 60 other words, when there is no resistance offered to the rotation of the shaft B, a yielding connection is interposed between the turbine and the shaft, which normally retains the ports e' in the relation to the ports b' shown in Fig. 4 when the engine is unloaded,

but which when a load is imposed upon the engine and the rotation of the shaft is consequently retarded permits the turbine to relatively move ahead of the shaft a slight distance allowed by the pin b and slot d, so that 70 the ports e' and b' are brought into full registry. Such yielding connection is shown as embodied in a spring rod or wire F, secured at its lower end f to the shaft B and adapted to engage at its opposite ends with a hole f² 75 in the adjacent side wall D² of the turbine to locate the ports e' in register with the ports b' or to engage a hole f' when the ports e² are to register with the ports b'.

H indicates an emery-wheel which surrounds 80 the reduced end B³ of the shaft and is retained thereon by the nut G³. It is of course obvious that the rotary motion imparted to the shaft B by the turbine may be utilized for other purposes than that of driving an emery-wheel. 85

The operation of our invention is as follows: When it is desired to rotate the shaft B in the direction indicated by the arrow in Fig. 3, the end of the spring-rod F is inserted in the hole f', which brings into registry the ports e' with the ports b'. The motive fluid then passes through the conduit C', tube c', annular groove c, ports b³ to the hollow interior B² of the enlarged portion B' of the shaft, thence through the ports b', and escapes through the 95 ports e² and is directed by them against the curved surfaces d² on the respective vanes D'. When resistance is offered to the rotation of the shaft B—as, for instance, when the emery-wheel is in contact with the surface being 100 worked upon—the impact of the fluid-pressure upon the surfaces d² of the vanes rotates the turbine forwardly with respect to the shaft the slight distance permitted by the slot-and-pin connection, such movement being permitted by the resiliency of the spring-rod F. When the resistance to the rotation of the 105 shaft is removed, the resilience of the spring-rod relatively rotates the turbine and shaft in a reverse direction, so that the registration between the ports e' and b' will be restricted, 110 thereby diminishing the flow of motive fluid through the turbine, resulting in a saving of the motive fluid and in avoiding the wear upon the engine which would result from the 115 racing or rapid rotation which would occur if the maximum discharge of fluid-pressure continued. When it is desired to rotate the turbine, and consequently the shaft in an opposite direction, the end of the spring-rod F is disengaged from the hole f' and inserted in the hole f², as indicated in Fig. 4, at which time, 120 when there is no load upon the engine, a restricted series of passage-ways is afforded through the ports b' and ports e', through which motive fluid passes into contact with the surfaces d' on the respective vanes D'. When a load is imposed upon an engine—such, for instance, as the engagement of the 125 emery-wheel H with material to be worked 130

upon—the impact of the motive fluid upon the vanes causes the turbine to rotate slightly ahead of the shaft, thereby bringing into full registry the ports *e*' and *b*', such relative movement between the turbine and shaft being permitted by the resiliency of the spring-rod and being limited by the engagement of the pin *b* with the end of the slot *d*.

From the foregoing description it will be observed that we have invented an improved rotary engine of the turbine type, in which the discharge of motive fluid therethrough is automatically regulated according to the load upon the engine and which may be readily so adjusted as to rotate in either direction.

While we have shown our invention as adapted to rotate an emery-wheel, it is of course obvious that it is capable of use wherever the rotation of a shaft may be availed of, and while we have shown three radial vanes it is evident that such number may be increased or diminished, it being only necessary that ports should lead to the opposite sides of such vanes, the ports on corresponding sides of the vanes being capable of simultaneous registry with supply-ports to impart rotary motion in one direction and the ports on the opposite corresponding sides of the vanes being capable of simultaneous registry with supply-ports upon slightly rotating the turbine with respect to such supply-ports.

While we have described more or less precisely the details of construction, we do not wish to be understood as limiting ourselves thereto, as we contemplate changes in form, the proportion of parts, and the substitution of equivalents as circumstances may suggest or render expedient without departing from the spirit of our invention.

Having fully described our invention, what we claim as new, and desire to secure by Letters Patent, is—

1. In a rotary engine, the combination with a plurality of vanes, of a rotary driven element upon which said vanes are adjustably mounted, means for discharging motive fluid through said driven element against corresponding sides of said vanes to impart rotary motion thereto, and means for automatically varying the discharge of motive fluid according to the resistance offered to the rotation of the vanes.

2. The combination with a turbine comprising a hub and radial vanes projecting therefrom, of a rotary support upon which said turbine is mounted, said turbine and support having registering ports through which motive fluid passes into contact with the surfaces of the vanes, and means for automatically varying the degree of registry of said ports according to the resistance offered to the rotation of said support.

3. The combination with a turbine comprising a hub and radial vanes projecting therefrom, of a rotary support upon which said

turbine is mounted, said turbine and support having registering ports through which motive fluid passes into contact with the surfaces of the vanes, a yielding connection between said turbine and support tending to retain the ports therein in partial registry, and a stop for limiting the relative rotation of said turbine upon said support when the ports therein are in full registry.

4. The combination with a turbine comprising a hub and a plurality of vanes carried by the hub, of a hollow rotary cylindrical support upon which said hub is rotatively mounted, said hub having a series of ports therethrough adjacent to the corresponding sides of the vanes and a second series of ports therethrough adjacent to the opposite corresponding sides of said vanes, said support having a series of ports therethrough, means for adjusting the position of the turbine upon said support whereby either of said series of ports through the hub may be brought into registry with the ports through the support, and means for supplying motive fluid to the hollow interior of said support.

5. The combination with a turbine comprising a hub and a plurality of vanes carried by the hub, of a hollow rotary cylindrical support upon which said hub is rotatively mounted, said hub having a series of ports therethrough adjacent to the corresponding sides of the vanes and a second series of ports therethrough adjacent to the opposite corresponding sides of said vanes, said support having a series of ports therethrough, means for adjusting the position of the turbine upon said support whereby either of said series of ports through the hub may be brought into registry with the ports through the support, a yielding connection between said turbine and said support tending to retain the series of ports in said support in partial registry with the coöperating ports in the hub, said connection permitting said ports to fully register upon the hub moving relatively to the support when resistance is offered to the rotation of the support, and means for supplying motive fluid to the hollow interior of said support.

6. The combination with a turbine comprising a hub and radial vanes projecting therefrom, of a rotary support upon which said turbine is mounted, said turbine and support having registering ports through which motive fluid passes into contact with the surfaces of the vanes, a spring-rod rigidly secured to the support and engaging said turbine to so relatively locate the turbine about the support that the ports therein will be in partial registry, said rod adapted to yield when resistance is offered to the rotation of said support to permit the turbine to move relatively to the support thereby bringing into full registry the coöperating ports.

7. The combination with a turbine comprising

- ing a plurality of vanes, of a rotary cylindrical support upon which said turbine is rotatively mounted, said turbine having a series of ports leading to the corresponding sides of the vanes and a second series of ports leading to the opposite corresponding sides of the vanes, said support having a series of ports therethrough adapted to register with either series of ports through the turbine, a spring-rod rigidly secured to said support and removably engaging said turbine to so position the same upon the support that either set of ports therethrough will be in partial registry with the ports through the support, said rod adapted to yield when resistance is offered to the rotation of said support to permit the turbine to move relatively to the support and the ports thereby brought into full registry.
8. In a turbine, the combination with a shaft, of means for rotatively supporting said shaft, a plurality of radial vanes adjustably mounted upon said shaft, and means for discharging motive fluid through said shaft against either side of said vanes whereby said shaft may be rotated in either direction.
9. In a turbine, the combination with a shaft, of means for rotatively supporting said shaft, a plurality of radial vanes mounted upon said shaft, means for discharging motive fluid through said shaft against either side of said vanes whereby said shaft may be rotated in either direction, and means for varying the discharge of motive fluid against

the vanes according to the resistance offered to the rotation of the shaft.

35

10. In a turbine, the combination with a rotary driven element having a supply-passage therein and a radial port leading from the supply-passage, of a rotary driving element surrounding and movable relatively to said driven element and having a passage in register with said port, and means for adjusting the position of said driving element upon said driven element to vary the degree of registry between said port and passage.

40

11. In a turbine, the combination with a rotary driven element having a central supply-passage and radial ports leading therefrom, of a driving element surrounding and adjustably supported upon said driven element and having passages in register with said ports through which motive fluid is discharged, and means for automatically adjusting the position of the driving element upon the driven element to vary the degree of registry between said ports and passages according to the resistance offered to the rotation of said driven element.

45

In testimony whereof we sign this specification in the presence of two witnesses.
